UNITED STATES PATENT OFFICE

2,095,216

MULTIPLE ROLL FULLING MILL

James D. Hunter and Ernest Cannity, North Adams, Mass., assignors to The James Hunter Machine Company, North Adams, Mass., a corporation of Massachusetts

Application December 24, 1936, Serial No. 117,572

1 Claim. (Cl. 26—20)

The present invention relates to fulling mills, and aims to increase the efficiency and quality of work of the mill, and to simplify the manipulation thereof.

5 The invention provides a novel and improved form of guide or stretcher capable of exerting any desired degree of retarding force on the cloth, to bring it to the desired length-dimension, while additionally both aiding in the width-wise condensing and fulling action and limiting the number of strings composing a single bundle, to prevent overloading of the mill and defective work as indicated hereinbefore.

10 Other features of the invention are as will be made plain hereinafter.

15 An illustrative embodiment of the invention is set forth in the accompanying drawings, in which,—

Fig. 1 is an elevation in section on a vertical 20 longitudinal plane of the improved fulling mill.

Fig. 2 is a plan view of the front portion of the fulling mill of Fig. 1, with the top of the machine removed and omitting the driving mechanism.

25 Fig. 3 is an elevation looking into the opened front end of the mill, showing the improved stretchers.

30 In the housing 1 are suitable fixed bearings for the bottom-roll shaft 3 and floating bearings for spring-loaded top-roll shaft 5. Preferredly a separate pair of short opposing top and bottom rolls 7, 9, is provided for each guide-eye or stretcher 11 and consequently for each group or bundle of strings, the illustrated mill being designed to handle four bundles. The length of 35 each pair of short rolls is made adequate to deal properly with all the cloth capable of being put through a single stretcher without surplus tempting the attendant into overloading. Each opposing pair of rolls has its individual crimping box 13 with sides extending forward of the rolls into proximity to the stretcher, and with swinging tongue 15 depressed by weight W through conventional linkage.

40 45 Cross-girths 17 fixed on the interior of the side-walls 19 at equal distances above and below the level of the top of bottom rolls 9 support uprights 21 equipped at midlength with bearings 23 in which are held journals 25 integral with the guides or stretchers 11. These guides are preferredly formed of hollow noncorrosive metal, outlining an aperture having oppositely-facing convergent-sided extremities, being of general diamond shape with the angles of the diamond 50 rounded, this aperture having materially greater

height than width, the section being flattened or elliptical as shown in Fig. 1. To a prolonged journal of each guide or stretcher a forked arm 27 is fixed, in the forked end of which is mounted a swivel-nut which is in screw-threaded engagement with the shank of adjusting screw 29 equipped with hand-wheel 31 outside the housing directly above the doors giving access into the front of the machine. A collar 33 is applied to each screw just inside the housing.

5 10 15 20 25 30 35 40 45 50 55 By rotating the screw 29 through hand-wheel 31, each guide or stretcher 11 can be given any desired degree of obliquity with relation to the line of travel of the bundle of cloth passing through such eye in its course from whip-roll 35 to the nip of the opposing rolls 7, 9. The more oblique the angle between the plane of the guide or stretcher and such line of travel, the more tendency there is for the bundle of cloth to wedge into the extremities of the diamond shaped aperture, as a result of the cloth's resistance to being forced into a devious path. Being held into a compact bundle by engagement with the oppositely-facing V-shaped ends of the diamond, while simultaneously confined by the sides of the diamond adjacent the journals, an extremely powerful frictional grip upon the bundle of strings of cloth passing through the eye is accomplished without the straining or fracture of the yarns at the outside of the bends formed by prior types of stretchers which force the cloth into a crooked path through the use of transverse bars. The shaping of the improved guide or stretcher permits generous extension of the depth of its section in the direction of travel of the cloth, whereby its bearing surface on the cloth is greatly increased, with lessened damage to the fabric.

The size of the diamond shaped opening in the guides or stretchers 11 through which the bundle 40 of strings must pass to reach the rolls is such as to limit the volume of cloth definitely to the maximum amount which can be properly worked and fulled between a single pair of the correspondingly limited opposed rolls 7, 9, or at any 45 one located in the length of full-width rolls.

While we have illustrated and described one form in which the invention may be embodied, we are aware that many modifications may be made therein by any person skilled in the art, 50 without departing from the scope of the invention as expressed in the claim. Therefore, we do not wish to be limited to the particular form shown, or to the details of construction thereof, but

What we do claim is:—

In a cloth fulling mill, in combination, opposed rolls propelling the cloth, a guide through which the cloth passes having oppositely-facing convergent-sided extremities, transversely extending journals intermediate such extremities, a lever fixed to one of such journals, and manu-

ally-operable means in connection with such lever adjustably determining the angular relation of the guide with respect to the line of travel of the cloth passing therethrough.

JAMES D. HUNTER.
ERNEST CANNITY.

CERTIFICATE OF CORRECTION.

Patent No. 2,095,216.

October 5, 1937.

JAMES D. HUNTER, ET AL.

It is hereby certified that error appears in the printed specification of the above numbered patent requiring correction as follows: Page 1, second column, line 46, for the word "located" read location; and that the said Letters Patent should be read with this correction therein that the same may conform to the record of the case in the Patent Office.

Signed and sealed this 16th day of November, A. D. 1937.

Henry Van Arsdale,
Acting Commissioner of Patents.
